UNITED STATES PATENT OFFICE

157,315

LAWN SPRINKLER

Herbert S. Ingham, Roslyn Estates, and Charles
K. Wilson, East Williston, N. Y.

Application November 4, 1949, Serial No. 5,876

Term of patent 14 years

(Cl. D91—1)

To all whom it may concern:

Be it known that we, Herbert S. Ingham and Charles K. Wilson, citizens of the United States, respectively residing at The Serpentine, Roslyn Estates, county of Nassau, State of New York, and 204 Howard Street, East Williston, Long Island, State of New York, have invented a new, original, and ornamental Design for a Lawn Sprinkler, of which the following is a specification, reference being had to the accompanying drawings, forming part thereof, in which

Fig. 1 is a side elevational view of a lawn sprinkler, showing our new design;

Fig. 2 is a perspective view of the lawn sprinkler shown in Fig. 1.

The opposite side of the device is substantially the same as that shown in Fig. 1.

We claim:

The ornamental design for a lawn sprinkler, as shown and described.

HERBERT S. INGHAM.
CHARLES K. WILSON.
